UNITED STATES PATENT OFFICE.

FRANK E. BRIXIUS, OF MANITOWOC, WISCONSIN, ASSIGNOR TO MANITOWOC ELECTRIC IMPLEMENT CO., OF MANITOWOC, WISCONSIN.

ELECTROMAGNETIC VIBRATOR.

1,230,857.

Specification of Letters Patent. Patented June 26, 1917.

Application filed October 21, 1916. Serial No. 126,841.

To all whom it may concern:

Be it known that I, FRANK E. BRIXIUS, a citizen of the United States, and resident of Manitowoc, in the county of Manitowoc and 5 State of Wisconsin, have invented certain new and useful Improvements in Electromagnetic Vibrators; and I do hereby declare that the following is a full, clear, and exact description thereof.

10 The present invention relates to new and useful improvements in vibrating devices, and is more particularly directed to the provision of means for vibrating pattern plates disposed in molds, whereby the plates 15 may upon vibration be disengaged from the sand of the mold, to permit ready withdrawal of the plates.

It is primarily the object of the invention to provide a vibrating device which is of an 20 exceedingly simple and compact nature, and the present invention consists essentially in the provision of an electro-magnet loosely connected with a body of magnetic material and resiliently urged therefrom whereby 25 upon the passage of successive electric impulses through said electro-magnet, it will be successively energized and deenergized and through the co-action of the resilient means procure vibratory motion of the magnetic body, it being appreciated that the 30 principle involved may be applied in many other instances than in vibrating pattern plates of molds.

A more detailed object resides in the provision of such a vibrating device which is 35 adapted to be detachably yet rigidly connected with a pattern plate or other work member.

With the above and other objects and advantages in view, the invention resides more 40 particularly in the novel combination, arrangement and formation of parts more particularly hereinafter described and particularly pointed out in the appended claims.

45 In the drawings

Figure 1 is a longitudinal sectional view through a vibrating device constructed in accordance with the present invention, and

50 Fig. 2 is a sectional view through the vibrator, the section being indicated by line 2—2 of Fig. 1.

Referring now to the drawings as exemplified, the vibrator is particularly adapted for use in connection with pattern plates

55 for molds and embodies a base plate 1

formed of iron or other magnetic material having a flange 1' for attaching it to a part associated with the mold. A metallic thimble 2 is riveted or otherwise secured to the magnet member 1 and this thimble carries 60 the usual magnet windings 3. The thimble is provided with a rectangular core opening 4 for the reception of laminated core 5, the same as shown being formed with an outer shell piece 6 bent upon itself to form an upper loop and interposed between the side legs of the same are a series of thin plates which are riveted to said side plates whereby the same is firmly secured. The upper board portion of the core is provided with 65 an aperture through which is extended a headed rod 7 that projects beyond the upper flange of the thimble and extends through an aperture in the supporting bar 8. The rod has fitted thereabout a coil spring 9 which is 70 interposed between the bar 8 and suitably disposed nuts 10 that are in threaded union with the end of the rod. The opposite end of the core as shown is normally held slightly clear of the magnet member or base 75 plate 1 by the spring 9 and when the magnet is energized in the usual manner the core will be caused to vibrate rapidly and thus exert a series of taps upon said plate to perform the necessary functions due to 80 the electric impulses being successively passed through the magnet to energize and deenergized the same.

While I have shown and described specifically one form of my invention it is 85 manifest that the structural forms may be varied within the knowledge of a skilled mechanic without departing from the spirit of said invention.

90 What is claimed is:

1. A vibrating device comprising, in combination, a magnetic base having magnet windings carried thereby, a core disposed in an opening in said windings, said core consisting of a shell bent upon itself to 95 form an upper loop, and laminæ secured between the side legs of the shell, a supporting bar secured to the top of said windings, and spring means engaging said shell and supporting bar to urge the core upward, 100 said core being adapted to vibrate rapidly and thus exert a series of taps upon said base when the magnet is energized, substantially as described.

2. A vibrating device comprising, in com- 110

bination, a magnetic base plate having
means carried thereby for securing the same
to work material, a metallic thimble secured
5 by said base plate, magnet windings carried
by said thimble, said thimble having a rec-
tangular core opening extending there-
through, a shell bent upon itself to form an
upper loop, a core interposed and secured
10 between the side legs of said shell, the upper
looped portion of said shell having an open-
ing therein, a supporting member secured to
the top of said thimble and extending across
said core opening and having therein an
aperture alining with the opening of the

core shell, a headed bolt passing up through 15
the openings in said shell and supporting
member, and a spring coiled around said
bolt and restricted between said supporting
member and a nut on the upper end of said
bolt, substantially as described. 20

In testimony that I claim the foregoing I
have hereunto set my hand at Manitowoc, in
the county of Manitowoc and State of Wis-
consin, in the presence of two witnesses.

FRANK E. BRIXIUS.

Witnesses:

RUDE STORKINGER,
J. S. ZIPPENER.
